REPOSITIONER MACHINE

Norman W. Lyon, Springfield, Mass., assignor to
 Package Machinery Company, Springfield,
 Mass., a corporation of Massachusetts

Application December 12, 1946, Serial No. 715,816

2 Claims. (Cl. 86—48)

1

This invention relates to a machine for rapidly repositioning and verifying the position of cartridges in link belt ammunition and has for an object the provision of a small light portable machine of such easily running character that hand operation of the machine is adequate in obtaining the required speed with which the cartridges are repositioned within the link belt.

A hand crank is provided to feed the assembled link belt ammunition through the machine until it protrudes on the opposite side and a novel feature is hereby introduced that an operator may grasp the end of the protruding link belt and pull said belt its entire length by hand through the machine as fast as desired and the proper positioning action on the cartridges will take place as he does so, eliminating the necessity of turning the hand crank.

It is known that cartridges allowed to remain within the links of link belt ammunition for a period of time, especially when subjected to salt air and moisture, will corrode and become lodged within said links so that their easy separation may become difficult, making it dangerous to run such a link belt through an automatic machine gun. Therefore, another feature of this machine is the fact that it will displace each cartridge from its existing position within the respective links of said link belt, whether already in desired alignment or not, to break any corrosion or undesired tightness, and then reposition each cartridge for proper alignment within said belt necessary for efficient operation in an automatic machine gun.

Another feature of this machine is its capability of aligning cartridges within links of different character which require a different location upon their respective cartridges for proper alignment within a machine gun for efficient operation thereof, simply by shifting an adjusting handle to the designated position on the machine for properly handling either type of link desired.

Referring to the drawings:

Fig. 1 is a small scale top plan of the entire machine showing the link belt ammunition entering said machine with the cartridges noticeably misaligned and also protruding in perfect alignment after having been processed within said machine;

Fig. 2 is a partial longitudinal section taken on line 2—2 of Fig. 1 with parts broken away and in adjustment for properly aligning M-7 type links upon their respective cartridges;

Fig. 3 is a sectional detail view taken on line 55

2

3—3 of Fig. 2 showing the several aligning plungers and extractors radially spaced and supported in a cylinder mounted upon a supporting drive shaft;

5 Fig. 4 is a right hand end view of Fig. 2 with parts broken away and diagrammatically shows the infeed and discharge line of travel of the link belt ammunition through the machine in the direction of the arrows;

10 Fig. 5 is a vertical sectional view taken on line 5—5 of Fig. 2 showing the cartridges in mesh with the radial pockets of the feed wheel;

15 Fig. 6 is a left hand end view of Fig. 2 and shows the adjusting handle provided for adjusting the machine to properly care for the alignment of cartridges within M-7 or M-3 type of links respectively;

Fig. 7 shows a cartridge properly placed within an M-7 link for efficient and accurate use in an automatic machine gun;

20 Fig. 8 is a similar view showing the proper position of a cartridge within an M-3 link;

Fig. 9 is a detail sectional view taken on line 9—9 of Fig. 4 through the infeed channel of the machine;

25 Fig. 10 is a similar detail view taken on line 10—10 of Fig. 4 showing the construction of the discharge chute;

Fig. 11 is a top plan detail of one of the several combination plunger and extractor devices assembled as a unit with certain parts broken away; and

30 Figs. 12, 13 and 14 are successive views in section showing the different positions attained by each cartridge as it is moved back and forth within the links by the extractors and plungers respectively to break any seal between it and said links before it is finally properly positioned within said links by said plungers.

35 40 Referring to the drawings, the entire machine is mounted upon a comparatively small base 1 and said base is provided at each end thereof with handles 2, providing an easy method for manually carrying said machine where desired.

45 An infeed channel 3 is provided for supporting the link belt ammunition thereon comprising cartridges K and links L. A discharge channel is provided in continuous alignment with said infeed channel (Fig. 5).

50 A central longitudinal shaft 4 is mounted for rotation in suitable bearings in front and rear end frames 5 and 6 respectively, secured to base 1. The shaft 4 has keyed to it, on a shouldered portion 7, a cylinder 8 which contains the pusher and extractor units slidably mounted in cham-

bers 9 equi-spaced circumferentially around the axis of shaft 4, for rotation with said shaft. Also mounted on said shouldered portion 7 and adjacent cylinder 8 is a wide drum-like feed wheel 10 provided on its periphery with equi-spaced pockets 11 in which the cartridges of the link belt are adapted to mesh for being fed through the machine. Cylinder 8 and feed wheel 10 are aligned on the same keyway which runs the entire length of the shouldered portion 7 of shaft 4 and are bound together for rotation with said shaft by a spanner nut 12 threaded as shown in Fig. 2 which tightly binds them as a unit against shoulder 13 on said shaft 4. At the forward end of shaft 4 two sprockets 14 and 15 are splined for rotation with said shaft and are adapted for horizontal adjustment thereon and secured in position by spanner nuts 16 and 17, one at each outside face of said sprockets and with a spacer 18 located between said sprockets to keep them in proper relation. The sprockets 14 and 15 each provide on their periphery pockets or recesses in which the forward portion of the cartridges rest and mesh for being fed through the machine.

During the travel of the link belt through the machine, the links L do not mesh with the feed wheel 10 but are guided between the side of the pockets 11 of said feed wheel and the side of the pocket of sprocket 14, and they bear against the latter mentioned side 14a which serves as an end abutment for holding said links to an accurate position when the cartridges are pushed into place within said links by the positioning means which will be described later. Likewise, the side 11a of pockets 11 in feed wheel 10 serves as an abutment for said links when the cartridges are pulled from within them by the extractors when breaking any seal between cartridges and links, which action will also be described later.

Cylinder 8 has formed therein a plurality of equi-spaced chambers or bores 9 radially disposed from the center of supporting shaft 4. Each chamber or bore 9 contains a plunger assembly comprising two independently slideable members, viz. a pusher 21 and an extractor 22. The forward ends of each member are adapted to be brought into successive alignment with the butt ends 19 of cartridges K as the latter are carried over the top of the feed wheel 10 in pockets 11. The forward ends of the extractors are provided with hook shaped members 23 to engage the rims of said cartridges and pull them from within their respective links a short distance to break any seal or tight joint between said cartridges and said links for their eventually easy separation when used as link belt ammunition in a machine gun.

Radially extending from the center of each bore 9 toward shaft 7 is a slot 24 in said cylinder 8 for the purpose of preventing any rotation, within said bore, of the extractor plunger which is slidably mounted therein and also provides a longitudinal slot running parallel to shaft 4 for the extractor hook 23 to travel within while acting upon the cartridge. The combination of bore 9 with slot 24 depending from it forms a key hole shaped passageway through cylinder 8. The pusher 21 is crescent shaped to fit the upper cylindrical portion 9 of said key hole opening, while the extractor plunger is thin and nearly square shaped to slidably fit partially within the depending slot 24 of cylinder 8 and partially within the slotted portion 25 of pusher 21, thereby acting as a reciprocating key to prevent pusher 21 from

rotating within the bore 9 in cylinder 8. As shown in Fig. 2, each pusher 21 carries at its left hand end a cam roller 31 mounted on a bearing pin 30, and each extractor plunger 22 similarly carries a roller 36 mounted on a bearing pin 35.

A housing 40 is secured to rear end frame 6 by long screws 37. Within said housing are two barrel cams of different diameter, the larger one to control the action of the pushers 21 through the rollers 31, and the smaller to simultaneously control the action of the extractors 22 by the rollers 36. The two barrel cams are stationary and are formed with cylindrical cam slots A and B in which the several rollers 31 and 36, respectively, travel as they are carried in rotation with cylinder 8 and shaft 4. The two barrel cams with their cam slots A and B are formed by an assembly of four rings 46, 43, 45 and 41, the rings 43 and 45 being integrally joined, and ring 41 being spaced from ring 45 to form the positively acting groove A of the cam which operates the pushers 21 while ring 46 is spaced from ring 43 to form the positively acting groove B of the cam which operates the extractors 22, as best shown in Fig. 2. The several cam forming rings are held in assembled positions by the before mentioned long screws 37. The screws 37 pass through holes in housing 40 and member 45 and thread into end frame 6 to secure these several pieces together as a unit.

A gear casing 53 supports a pinion shaft 54, parallel to and above shaft 4, having a pinion gear 55 integral therewith. A hand crank 56 is secured to the extreme end of said shaft 54 by a clamping means 57. Casing 53 is rigidly secured to front end frame 5 by bolts 58. The front end of shaft 4 possesses an enlarged bearing surface 60 which is rotatably and slidably mounted in a needle bearing 61 journaled in front end frame 5. A reduced portion 62 on said shaft 4 has keyed to it at 63 an internal gear 65 secured in place by a binding nut 66. Pinion gear 55 is in constant mesh with internal gear 65 and as crank 56 is rotated in a clockwise direction shaft 4 will be rotated likewise simultaneously rotating sprockets 14 and 15 and feed wheel 10 with which the cartridges of the link belt ammunition are in mesh for advancing said belt through the machine.

A hold back is provided to insure a clockwise rotation of hand crank 56 and to prevent the weight of the incoming link belt ammunition from rotating the feed wheel in a counterclockwise direction, comprising a weighted pawl 71 pivoted by shaft 70 in boss 68 of casing 53. As shown in Figs. 2 and 4 the nose of pawl 71 engages internal teeth of gear 65 and has an outside lift off handle 73 to release it when desired.

Suitable guide ribs 74 and 74' integral with arcuate cover plates 75 and 76, as shown in Figs. 2 and 5, have been provided to confine the cartridges and links to the feed wheel 10 and sprockets 14 and 15 respectively during the repositioning process on said cartridges. The front cover 76 (Fig. 5) is pivotally supported on shaft 77 by a long hub portion 78 and a short hub 79 adjacent to collar 80 secured to said shaft 77. A combination latching and lifting handle 81 is pivoted at 82 on a projecting arm 83 integral with said hub 78. A stationary segment 84 secured to front end frame 5 is formed with two notches 85 and 86 approximately 180° apart into which handle 81 locks by means of two square latches 87 and 88 respectively, mounted at opposite ends of an arcuate base 89 of said handle 81. By the engage-

ment of said latches with said notches, the front cover 76 may be locked in a closed or open position respectively. A lift of handle 81 automatically disengages latch 87 from notch 85 as said handle 81 pivots on stud 82. Latch 88 will then contact arcuate surface 90 of segment 84 and ride on said surface during the further lift on handle 81 until finally latch 88 will engage notch 86 and thereby hold cover 76 in an open position. Shaft 77 that supports the aforesaid covers is rigidly held against rotation in end frame 5 by a set screw 91 and also in end frame 6 by a similar set screw 92.

As the hand crank 56 is rotated as described, shaft 4 together with sprockets 14 and 15, feed wheel 10, and cylinder 8 are also rotated as previously described. Cylinder 8 carries pushers 21 and extractors 22 which simultaneously act upon the butt ends of cartridges K confined within the radial pockets of feed wheel 10 and perform the following operations.

Referring to Fig. 5, center line I indicates the position where Fig. 12 is taken. Pusher 21 is at the end of its dwell back and is ready to start forward, in the direction of the arrow, toward the butt end of the cartridge. Extractor hook 23 is at the end of a short dwell forward and ready to start back again to contact rim R and move it to the dotted position R' to break any seal or tight joint between cartridge K and links L. As the extractor hook 23 pulls the cartridge from within its respective links L (Fig. 12), said links are prevented any lateral movement by their contact with the inside surface 11a of the feed wheel 10. Pusher 21 is at its extreme open or dwell back position to allow the entrance of incoming cartridges on the link belt. Said cartridges may be $\frac{3}{4}$ " too far out from normal position as indicated at R' or $\frac{1}{4}$ " too far in toward the links as indicated at R" (Fig. 12) and they will be properly cared for and repositioned as described. The full line position R indicates the normal position of the cartridge properly positioned within its respective link L. Referring to Fig. 5, center line II indicates the position where Fig. 13 is taken. The cartridge was left by the hook 23 as shown, in an extreme rearward position, and said hook is here shown moving forward, in the direction of the arrow, before the plunger 21 contacts the butt end 19 of the cartridge during its travel forward. Center line III on Fig. 5 indicates the position where Fig. 14 is taken. Said figure shows the cartridge left at the proper position within its respective links by the pusher 21 at the end of its forward stroke and about to return in the direction of the arrow and dwell way back in the position shown in Fig. 12 as the feed wheel shaft continues to rotate and until it reaches the position indicated at I again when it will repeat the action just described on another cartridge. Extractor hook 23 is at the end of a short dwell sufficient for the cartridge to leave the pocket of the feed wheel 10 after traveling past center line III. Then hook 23 slowly moves in the direction of the arrow (Fig. 14) until it reaches a position corresponding to that shown in Fig. 12, during which time feed wheel 10 will rotate from position III to position I. The hook 23 is centrally located in the slotted end 93 of extractor 22. It is pivoted to extractor 22 on pin 94 and has a tail portion 95 extending in the opposite direction from said hook 23. Said tail 95 is held in a depressed position by a spring 96 mounted between its end and the upper portion of extractor slot 93. Said spring forces said hook 23 in an upward

direction so that positive contact will be made with the rim of the cartridge as the occasion presents itself. During the absence of a cartridge within a pocket, the upward movement of said hook is limited by the provision of a stop lug 97 which will contact the vertical wall 98 of extractor 22. As the pusher 21 pushes the cartridge into its respective links L (Fig. 14), said links are prevented any lateral movement by their contact with the inside surface 11a of the guide sprocket 14. Thus the action of one repositioning unit, comprising a pusher and an extractor has just been described and it will be understood that all other such units confined within the several radially spaced chambers of cylinder 8 will simultaneously act upon the succeeding cartridges within the link belt as said cartridges come into successive axial alignment with said repositioning units.

The discharge channel 99 consists of suitable supports 100 (Fig. 10) upon which cartridges rest as they depart through said channel. Upper guides 101 are accurately spaced from said supports to allow the free travel of the cartridges between them, and also provide a substantial support against which the cartridges bear and easily slide, especially when said belt is pulled through the machine by hand, as previously described.

Provision has been made to properly position cartridges with either of two types of links, namely the M-7 (Fig. 7) or the M-3 type, each of which requires a different measurement from the butt end 19 of the cartridge to the extreme outer edge of the links as clearly shown in Figs. 7 and 8. It will be noted from these two figures that link M-7 has lugs depending from the outside edges of the two lower loops while the M-3 type shown in Fig. 8 has none at all. To accurately fire the cartridges from either type link belt structure in an automatic machine gun, the dimensions shown on the drawing must be adhered to. The machine set up just described has been for positioning cartridges within the M-7 type links.

To adjust the machine for positioning cartridges within the M-3 type links, an adjusting handle 102 has been provided (Fig. 6). The operator must release the spring pressed detent 103 by pulling out on knob 104 and then move the handle clockwise by handle 102 to the M-3 position 105. The lifting handle 2 prevents adjusting handle 102 from being moved in the wrong direction. When said handle 102 is moved from M-7 to M-3 position, shaft 4 which carries feed wheel 10, supports sprockets 14 and 15, and cylinder 8, possessing the pusher and extractor units, is moved in a longitudinal manner within the machine. Cam slots A and B, for said pushers and extractors respectively, keep their same relative positions within the housing 40. This requires said pushers and extractors to deliver the same length of stroke at all times. A threaded sleeve 106 is mounted for rotation on threads 107 in hub 108 of housing 40. Handle 102 is secured by screws 109 to said sleeve 106 which carries ball bearing 110 therein. Shaft 4 is rotatably secured to said bearing 110 on reduced portion 111 by lock nut 112.

By this simple and accurate adjustment, shaft 4, and all that is secured thereto, moves laterally on needle bearing 61 at its right hand end, as shown in Fig. 2, and on screw threads 107 in hub 108 at its other end. Gear 65 is made deep enough to allow its movement to the dotted line position indicated at 113. The position of the

links, confined between the respective sides of feed wheel 10 and sprocket 14, will be moved laterally in relation to the fixed stroke of the plunger assembly. By maintaining the same plunger stroke the cartridges will not be pushed into the M-3 links so far as with the M-7 adjustment therefore acquiring the desired 3.80 dimension from the butt of the cartridge to the extreme edge of the link as desired.

An additional adjustment has been provided for precisely obtaining the position of the links of either type upon their respective cartridges by removing screws 109 and then rotating handle 102 to the right or left at intervals of 90° and re-placing said screws.

In the mechanism described, return springs for the working parts are not employed. Thus there is no resistance load to be overcome in the operation of the machine except the necessary work of repositioning the cartridges within their respective links several of which are being processed at one time. The frictional resistance of all moving parts is negligible and the maximum results in easy running character are obtained for this type of machine which has been stated before that to pull the link belt through by hand is superior to hand crank operation and equal to a power drive.

What I claim is:

1. A machine for repositioning the cartridges in the links of link belt ammunition which comprises, a rotatable drive shaft, means for driving said shaft, a feed wheel fixed to said shaft and having a plurality of peripheral pockets for receiving the linked cartridges as the belt is fed through the machine, a cylinder fixed to said shaft, a plurality of repositioning units reciprocably mounted in said cylinder and positioned in alignment one unit with each pocket of the feed wheel, each of said units comprising an extractor member provided on its end adjacent the wheel with a spring hook for engaging the rim

of a cartridge in the aligned wheel pocket and on its opposite end with a cam wheel, and a pusher member provided on its end adjacent the wheel with a head for engaging the base of said cartridge and on its opposite end with a cam wheel, and means operative upon rotation of said shaft to reciprocate said members relative to the cylinder and each other, said means comprising a stationary positively acting cylindrical cam with which the cam wheels of the extractor members engage to retract the extractor and displace the cartridge engaged thereby from its link, and a stationary positively acting cylindrical cam with which the cam wheels of the pusher members engage to advance the pusher into engagement with the displaced cartridge and reposition the latter in predetermined relation to its link.

2. A machine as in claim 1 having a sprocket shaped wheel secured to the drive shaft and spaced from the feed wheel, the adjacent faces of said sprocket and feed wheels forming abutments preventing transverse movement of the links during the displacement and repositioning of the cartridges in the links.
